UNITED STATES PATENT OFFICE.

JOHN HOWARD LACY, OF BOSTON, MASSACHUSETTS.

SAFETY RAZOR.

Application filed March 11, 1922, Serial No. 543,057. Renewed August 3, 1923.

To all whom it may concern:

Be it known that I, JOHN HOWARD LACY, a citizen of the United States, and resident of Boston, county of Suffolk, State of Massachusetts, have invented an Improvement in Safety Razors, of which the following description, in connection with the accompanying drawing, is a specification, like characters on the drawing representing like parts.

This invention relates to safety razors of the type known to the trade as the "Gillette" razor, such razors being constructed with a blade-supporting head having a guard, a transversely-flexible blade carried by said head, and means for clamping the blade to the head and for adjustably flexing the blade transversely.

In some razors of this type the blade-supporting head is formed with a channel located behind the guard, said channel extending from one end to the other of the head and being situated directly beneath the cutting edge of the blade. The advantage of having the channel extending directly underneath the cutting edge is that the adjustment of the cutting edge due to a greater or less degree of flexing of the blade is accomplished without changing appreciably the distance of the cutting edge from the guard or from the point at which the guard bears on the skin in the act of shaving.

I have found from experience, however, that where a razor is made with the channel running the full length of the head, the corners of the blade are not sufficiently protected and the result is that unless a person uses a razor very carefully the corners are apt to catch in and cut the skin, especially where the razor is being manipulated around a portion of the face having an uneven contour.

It is a principal object of my present invention to provide a safety razor with means for properly protecting the corners of the blade so as to prevent any danger of cutting the face with the corner during the shaving operation, while at the same time leaving the protected corners free for use in shaving.

I accomplish this object by making the portions of the guard opposite the corners of the blade that are to be protected somewhat higher than the main portion of the

guard, such higher guard portions giving the desired protection.

In order to give an understanding of the invention I have illustrated in the drawings a selected embodiment thereof which will now be described after which the novel features will be pointed out in the appended claims.

Fig. 1 is a top plan view of a razor embodying my invention with a portion broken out.

Fig. 2 is an end view, also with a portion broken out.

Fig. 3 is a fragmentary side view.

In the razor herein shown 1 indicates the handle of the razor having a blade-supporting head 2 at one end thereof and provided on its opposite edges with a guard, the latter being herein shown as the end portions 15 of a row of teeth 3. 4 indicates the blade, which is of the transversely-flexible type, said blade being clamped to the head 2 by means of a blade-clamping cap 5. This cap is shown as having a screw-threaded stem 6 which extends through the handle 80 1 and which is engaged by a nut 7. The blade-clamping cap is also shown as provided with positioning pins 8 which extend through apertures in the blade and in the head 2. The head 2 is formed on each side with a channel 9 situated directly underneath the cutting edge 10 of the blade, said channel being formed in the teeth 3 constituting the guard. The presence of this channel which extends the full length 90 of the head forms a guard which extends from the edge of the head to the point 11 only, and also provides a construction in which the cutting edge 10 of the blade is separated from the guard or any portion 95 of the head throughout its entire length. With this construction any adjustment of the blade which is secured by flexing it more or less does not change appreciably the distance between the cutting edge 10 and the guard, so that the proper relation 100 between the cutting edge and guard are always maintained in all adjustments of the blade.

The parts thus far described are or may be all as usual in razors of this type and form no part of my present invention.

Where the channel 9 extends clear to the ends of the head 2 and the guard is of a uniform height, I have found from experience 110

that in manipulating the razor over a portion of the face having an uneven contour there is danger that the corners 12 of the blade will cut or injure the skin, this being due to the fact that the corners are not properly protected because of the presence of the channel 9 extending beneath them.

To obviate this danger I propose to provide the necessary protection for the corners 12 of the blade by making the portions of the guard 15 opposite said corners somewhat higher than the other portions of the guard so that these higher portions of the guard extend up to or possibly above the cutting edge of the blade. These blade-protecting portions of the guard are at the ends of the guard only and do not interfere at all with the proper functioning of the razor in shaving.

Where the guard is in the form of separate teeth 3, as herein shown, my invention may be carried out by making the portions of the end teeth, indicated at 3^a, which are situated outside of the groove or channel 9, somewhat thicker so that the upper face of these end teeth come in line with or perhaps slightly above the cutting edge 10 of the blade.

In the construction herein shown the teeth 3^a are made thick enough so that the portion 13 thereof where the outer face meets the channel or groove 9 stands slightly above the cutting edge. This is clearly shown in Fig. 2 from which it will be evident how these thickened portions 3^a of the guard function to protect the corners 12 of the blade and prevent them from cutting or injuring the skin during the shaving operation.

With this arrangement wherein the groove or channel 9 extends the entire length of the head, the full advantage incident to the use of the groove or channel is obtained, and at the same time the corners of the blade are completely protected, this being accomplished without in any way interfering with the proper functioning of the razor during the shaving operation.

While for illustrative purposes I have herein shown a selected embodiment of the invention as applied to a razor having a channel in the head beneath the cutting edge of the blade yet I do not wish to be limited to the constructional features shown, nor is the use of the invention limited to the particular form of razor illustrated as I believe I am the first to provide a razor having a transversely - flexible blade and means for adjusting it, with a guard so constructed that the portions thereof opposing the corners of the blade have guarding faces situated sufficiently above the other portions of the guard to protect the blade corners, which

raised portions of the guard are separated from the cutting edge so as to permit free use of the protected corners for shaving purposes.

I claim:

1. A safety razor comprising a blade-supporting head having a guard, a transversely-flexible blade and means for adjustably clamping said blade to said head, said head having a channel behind the guard and situated beneath the cutting edge of the blade, which channel extends the full length of the blade so that the cutting edge of the blade throughout its length is separated slightly from any portion of the head, the portions of the guard opposing the corners of the blade having their outer faces situated slightly above the remaining portion of the guard thereby amply guarding but permitting the use of said blade corners.

2. In a safety razor, the combination with a blade-supporting head having a row of teeth forming a guard, of a transversely-flexible blade, and means for clamping said blade to said head, said teeth being formed with a channel located beneath the cutting edge of the blade and which extends the full length of said cutting edge whereby the cutting edge throughout its entire length is out of contact with any portion of the head, the end teeth having their guard surfaces situated slightly above the guard surfaces of the other teeth thereby amply guarding but permitting the use of the corners of the blade.

3. A safety razor comprising a blade-supporting head having a guard, a transversely-flexible blade and means for adjustably clamping said blade to said head, the portions of the guard opposing each corner of the blade having its guarding face situated sufficiently above the other portions of the guard to protect the blade corner, said raised portions of the guard being separated from the cutting edge so as to permit free use of the protected corners for shaving purposes.

4. In a safety razor, the combination with a blade-supporting head having a row of teeth forming a guard, of a transversely-flexible blade and means for clamping said blade to said head, the end teeth of the guard having their guard surfaces situated slightly above the guard surfaces of the other teeth and said raised guard surfaces of the end teeth being spaced from the cutting edge of the blade, whereby the corners of the blade are available for use but are amply protected.

In testimony whereof, I have signed my name to this specification.

JOHN HOWARD LACY.
